DOOR KNOB ASSEMBLY

Thomas G. Sconzo, Sayville, and Andrew A. Ribaudo, Brentwood, N.Y.; said Ribaudo assignor to said Thomas G. Sconzo, Sayville, N.Y.

Filed June 21, 1960, Ser. No. 37,704
6 Claims. (Cl. 292—227)

This invention relates to a door knob assembly. More particularly, it relates to a non-rotatable knob assembly for ordinary doors, and storm, screen and other types of doors.

It is an object of the present invention to provide a knob assembly having locking means wherein the need or requirement for screws or other type of locking or attaching members is eliminated.

It is another object of the present invention to provide an adjustable door knob assembly having interconnectable, lockable parts which can be relatively and easily separated from or connected to a door without requiring any screws for fastening the assembly to the door.

A further object of the present invention is to provide an adjustable knob assembly for attachment to doors of different thicknesses wherein the component parts of the knob assembly can be readily connected to each other forming a locking device which can be effectively used to keep doors locked or closed.

Another object of the present invention is to provide a door knob assembly comprising interconnecting knobs, with depressible means, a plurality of adjustable joining members, locking means, and plates to keep the knobs separate from each other while at the same time permitting their coaction.

A specific object of the present invention is to provide a door knob assembly comprising a knob adapted to extend through the thickness of a door, another knob telescopically connectable with and adjustable with respect to the first knob and adapted to extend through a door, means extending through the knobs for adjusting the positioning of the knobs relatively of each other with respect to the door, locking means for the knobs, means on each knob for actuating the locking means, means for locking the knobs relatively of a door jamb, and plate means for said knobs.

Other objects and features of the present invention will become apparent from the following detailed description taken in conjunction with the accompanying drawings, wherein:

FIG. 1 is a fragmental, partly plan, partly sectional view of a preferred embodiment of the invention associated with portion of a door and a frame;

FIG. 2 is a vertical plan view of FIG. 1 looking in the direction of the arrows 2—2 in FIG. 1;

FIG. 3 is a detailed sectional view taken on line 3—3 of FIG. 1;

FIG. 4 is a sectional view taken on line 4—4 of FIG. 3;

FIG. 5 is a sectional view taken on line 5—5 of FIG. 3;

FIG. 6 is a side view of a male knob used in the preferred embodiment of the invention;

FIG. 7 is a plan view of a plate forming a part of the invention;

FIG. 8 is a side view of FIG. 7;

FIG. 9 is a rear plan view of the plate shown in FIGS. 7 and 8;

FIG. 10 is a bottom plan view of a setting member used in the invention.

FIG. 11 is a side view of a pair of setting members or plungers forming part of the invention;

FIG. 12 is a partly sectional, side view of the female knob;

FIG. 13 is a right end view of FIG. 12;

2

FIG. 14 is a longitudinal sectional view taken on line 14—14 of FIG. 12.

FIG. 15 is a view of removable locking means used for the relative adjustment of the male and female knob.

5 Referring now more particularly to the drawings wherein like numbers refer to like parts throughout, it will be noted that there is provided a knob assembly 15 which includes a hollow female knob 16, a hollow male knob 17, a plurality of interlockable, adjustable plunger members 18 and 19 insertable in and extending through the interior of the joined knobs so as to permit proper adjustment of their connected length and for each of the knobs, and a pair of plates 20 and 21, which are adapted to keep the knobs in relatively separate position with respect to a door once the whole assembly has been installed in the door. One of said plates as hereinafter described is provided with locking means.

10 Female knob 16 has an internally threaded shank 23 which extends through an opening 24 of plate 21 and opening 25 of door 26. Said shank 23 has a central hollow internally threaded portion 27 which continues and is adapted to merge with externally threaded shank 28 of knob 17. Said central portion 27 accommodates the forward threaded projecting shank portion 28 of male knob 17 as shown in FIG. 3. The projecting portion 28 is further provided with a central opening 29 for purposes hereinafter described.

15 It will be noted also that shank 23 is provided with a pair of longitudinal peripheral indentations 30 and 31 30 adapted to accommodate fingers 32 and 33 respectively of a work lock pin 34 which extends through a pair of openings 35 and 36 in wall 37 of said knob. The fingers of said lock pin 34, it will be noted are passed through the openings 35 and 36 into indentations 30 and 31, and fit indentations 38 and 39 of shank 28 of male knob, 17. The use of lock pin 34 after the two knobs are relatively adjusted is such that the knobs are interlocked by the lock pin 34 and cannot be further rotated relatively one of the other once they are set, unless said lock pin 34 is retracted to permit further adjustment of the knobs. The head of pin 34 extends beyond wall 37 which forms the floor of knob 16 so that the head extends into said hollowed portion of the knob.

20 Said wall 37 in the interior of knob 16 also has a central opening 41 through which extend plungers 18 and 19 to make contact with each other. These plungers may be relatively adjusted, as shown in the drawings, to allow for the thickness of the door to which the assembly is fixed.

25 When joined together the plungers then act as a unit in cooperation with the knobs as will be hereinafter further described. To the right of said wall 37 as seen in FIG. 3 and FIG. 14 is a spring 42 adapted to press against button 43 which is pivoted at one end to the inside knob 16 so that the button can be moved downwardly in said knob.

30 Said knob furthermore is provided with a pin 44 extending through openings of extensions 45 and 46 which between them form a slit 47 as seen in FIG. 12. Said pin 44 fits through one end of a tongue actuator 48 which pivots so that one end of the tongue extends into the interior of knob 16.

35 Said member 48 can be actuated around its pivot 44 by means of button 43, said button being inwardly pivoted at one end to spring plate 50 which extends upwardly from a ledge 51 in the interior of knob 16. Furthermore, said button 43, as shown, is kept in normally contacting position with rim 52 in the periphery of the knob by said spring member 42, but when said button is depressed against the action of the spring, it slidably contacts tongue 48 so as to actuate the same to extend into the interior of the knob thus permitting the opening and closing of the door 26 when used in conjunction with a

striker plate 53 fixed to and extending laterally of door jamb 54. Said tongue 48 pivotally mounted to the knob as shown is adapted to make and break a contact with striker plate 53 as shown in FIG. 1 of the drawing.

Male knob 17 is also hollow and provided with externally threaded shank 28 adapted to fit into the shank of female knob 16. Said male knob is also provided with a pair of longitudinal grooves 38 and 39 in its periphery so that with the corresponding grooves 30 and 31 in shank 23 of the female knob they can accommodate fingers 32 and 33 of the lock pin thereby permitting after proper adjustment of the knobs to form locking action.

Furthermore, said shank 28 as threaded permits its insertion into female knob 16. Said male knob as shown accommodates inner spring 55 which fits within the cavity of the knob, so as to hold button 56 pivotally connected to said knob in normally taut position against the rim 57 which extends around the outermost rim of the knob.

Before said knobs are assembled on the door 26, there are inserted in the shanks of the respective knobs two adjustable plungers 18 and 19. They can be engaged to any adjusted length depending on the thickness of the door so that the respective ends 58 and 59 can form respective contact with the respective buttons 56 and 43 of knobs 16 and 17. Each plunger shown is provided with spaced teeth 60 so as to permit relative intermeshing whereby the relative combined length is obtained at which the plungers are interlocked depending upon the thickness of the door 26 to which the assembly is attached and their contact with buttons 43 and 56.

In the event a connection has to be made with respect to the male and female knobs on door 26, it is necessary to provide for the proper length of the plungers 18 and 19 so that the proper and most efficient contact is made with side arm 61 of tongue 48 in female knob 16 through spring 55 in the male knob 17. The relative adjustment of said plungers is shown in FIG. 11 of the drawings.

In assembling the knobs on door 26, door plates 20 and 21 are provided one for each side of the door. Each has an opening through which the respective shank of the respective knob extends. Also, said plates are placed in such position that they are flush with the faces of the door as in FIGS. 1 and 3. Door plate 21 has locking means 22 and is set on the inside of door 26 accommodating the outside of shank 23 of female knob 16. It also permits a flat smooth contact with the door around its opening, while at the same time accommodating the knobs without showing any rough spots and the like.

Said plate 21, as indicated, is provided with slidable locking means 22 having spaced slidable arms 62 and 63 which are adapted to fit in and slide in parallel slots 64 and 65 respectively in said knob 16. Said locking mechanism is on the inside of said plate 21 and when extension 22 is raised or lowered with respect to the plate housing the locking member, the arms 62 and 63 slide in slots 64 and 65 and control the movement of tongue 48. Thus, by locking tongue 48, it cannot move inwardly, on its pivot, in slit 47 and tongue 48 is forced against striker plate 53, whereby the door is kept in fixed or locked position. It will be also noted that plate 21 has notches 66 adapted to accommodate bumps 67 on knob 16 so that the plate is held in firmly engaged position.

The male member as shown in the assembly is also provided with a plate 20 having an opening for shank 28 and part of the base of knob 17. Furthermore, said plate 20 also has a plurality of notches 68 for accommodating the peripheral bumps 69 of said knob.

Thus since the knobs and plates are assembled, the extensions of the plungers are in contact with each other and of such measured length and disposition that tongue 48 can be readily actuated or operated on contact of either button 56 or 43. By this assembly, if button 56 is depressed it will press against extensions 59 of plunger 19 thus pushing the plunger 18 against side piece 61 of tongue 48 so that said tongue is rotated inwardly of knob 16

around pivot 44 thereby releasing tongue 48 from locking contact with striker plate 53. If the door is to be opened from the inside, then button 43 is pressed inwardly of knob 16 and releasing contact with plate 53.

From the foregoing, it will be noted that when the male knob is connected with the female knob there is provided a continuous opening and the length of the insertion between the male and female knob is such that it will provide for the thickness of the door and it will be noted further that said knobs can be relatively adjusted so as to provide for any door thickness.

Once said knobs have been connected together through a door as shown in FIG. 3, it will be noted that no screws or bolts or nuts are required. Furthermore, in the event it is necessary to adjust the knobs with respect to each other after they have been locked, it is important that the locking means 22 which operates the rotation of one knob relatively of the other can be used so as to open up and disconnect the two knobs. Once said knobs are connected and adjusted, depending on the thickness of the door and the relative positioning of the plungers, the plates 20 and 21 remain in fixed position against the door 26. To adjust the locked assembly, it would be necessary to work under button 43 to slide the locking means 22 from the peripheral indentations in the shanks of the knobs.

Also, said tongue 48 pivotally connected to the female knob is adapted to form a locking engagement with striker plate 53, which is connected to the door jamb. Once this connection has been made, the knob assembly is permanently fixed to the door so that no further action is required.

There also is provided the proper esthetic appearance of the knob assembly on the door, by using a pair of plates namely 20 and 21, one of which goes on the outside of the door and the other one goes on the inside of the door so that the knobs will be properly anchored with regard to the opening in the door.

In order to hold said knobs at a desirable distance, it would be noted that plungers 18 and 19 make operable contact with the buttons of the respective knobs. The plungers each consist of a shaft on which there are provided a number of teeth so that one can be interlocked with the other half thus acting as an adjustable operating member with respect to the buttons of the knobs. Each is adapted to extend into the respective hollow of each knob so as to effect the proper operation of the assembly.

While a preferred embodiment of the invention has been shown and described, it is to be noted that changes as to form, arrangement and use of parts may be made without departing from the spirit and scope of the invention as claimed.

I claim:

1. A door knob assembly comprising an exterior and an interior plate for attachment to a door, said plates each having an opening therein, a female knob extending through one of said plates and said door, a male knob adapted to extend through the other plate and said door and be connected with the first said knob, latch means for the door hingedly affixed to one of the said knobs, plunger means adjustable as to length within and slidable longitudinally within said knobs, in engagement with said latch means for slidably unlatching said latch means, and sliding locking means for said latch means and engageable therewith in said interior plate to lock the latch means, said knobs having threaded means for engaging each other and adjustable for regulating the length of the distance of the one knob from the other.
2. A door knob assembly comprising a pair of plates

for both sides of a door and having openings for alignment with a door opening,

a female knob in one said plate and a male knob in the other said plate adapted for interconnection and extension through the door opening and so interconnected, and

further adapted by reason of their length to hold said plates in firm contact with a door when so interconnected,

longitudinally dimensionally adjustable plunger means within said knobs longitudinally slidable therein, compressible means on one said knob for sliding said plunger means in contact therewith,

latch means on another said knob for holding a door in position, in contact with and releasable by sliding of said plunger means,

compressible means on said another knob in contact with and actuatable to release said latch means, and

locking means on a said plate slidable to engage and immobilize said latch means, said knobs having threaded means for engaging each other and adjustable for regulating the length of the distance of one knob from the other.

3. A locking door knob assembly comprising a pair of rotatably threaded interconnectable hollow knob members having each a shank portion,

adjustable plunger means extending through the shank portions of said knob members, longitudinally insertable therein and rotationally immovable with respect thereto for prevention of rotation therebetween,

a pair of plates for said knob members adapted to be applied against the face of a door to which the assembly is to be attached and there retained by pressure of said knob members,

door locking means in one of said knob members comprising a protruding latch, and having a shape adapted to retain and be immobilized by an inserted slidable detent means, said slidable detent means being mounted on one of said plates and having an arm slidable into engagement with said door locking means for immobilizing engagement therewith.

4. A door knob assembly for connection with a door of any desired thickness having locking means on the jamb comprising a pair of plate members attachable to each side of said door, each of said members having an opening therein, said door having an opening therein corresponding with the opening in each of said plates so as to be coincidental with the longitudinal axis of said opening,

a knob having a threaded shank extendable through the opening of one of said plates,

another knob having a threaded shank extendable through the opening of the other plate and adapted to engage the other knob, each of said shanks having a hollow interior portion of prismatic section in longitudinal apposition,

spring means in each of said knobs,

a compressible button means on each knob held by said spring means in a normally extended position,

50

55

45

35

30

15

5

movable means on one of said knobs for making contact with said locking means on a door jamb, and extensibly adjustable

slidable plunger means in the hollow portions of the shanks of said knobs, contacting one said button means and the said movable means making contact therewith,

the other said button means being in direct contact therewith, whereby depression of either button means moves the movable means of making contact for unlocking from the door jamb;

the said one button means by pressing the slidable plunger means against the means for making contact,

and the other button means by pressing thereon directly.

5. A door knob assembly for use in connection with a door of any desired thickness having a door jamb, comprising a pair of plates each having an opening in alignment with the other,

said door having an opening therein coaxial with the opening on each of said plates,

a first knob extendable through the opening of one of said plates,

said knob having a bump abutting one of the said plates, and also having a shank extending through the opening thereof and of the door,

another knob extendable through the opening of the other said plate, having a bump abutting said other plate and a

shank adapted to engage the shank of the said first knob,

removable means for holding said knobs together, a tongue member pivotally extending from one knob forming a locking engagement with a fixed plate on a door jamb,

and locking means located in one of said plates for the said one knob for immobilizing the tongue member.

6. A tongue knob assembly for doors and the like comprising a pair of threaded interconnectable knobs having hollow square interior portions in line, adapted to pass through the opening of a door,

an outside plate for each of said knobs, adapted to fit against the door, a pair of lengthwise, adjustably interlocking plungers having a square interlocked outline extending through the interior of the knobs and slidably therein,

one of said knobs having a compressible button for sliding the plungers,

a tongue member pivotally mounted on the other said knob adapted to be actuated by a compressible button on the other said knob and by plunger sliding,

spring means in each said knob for keeping said buttons in extended position in the knobs,

and locking means in one of said plates for locking said tongue to prevent movement thereof.
